EMIL A. RUTISHAUSER, OF AURORA, ILLINOIS.

RAIL-JOINT.

1,307,885.

Specification of Letters Patent. Patented June 24, 1919.

Application filed November 9, 1916. Serial No. 130,454.

To all whom it may concern:

Be it known that I, EMIL A. RUTISHAUSER, a citizen of the United States, and resident of Aurora, in the county of Kane and State of Illinois, have invented a new and useful Rail-Joint, of which the following is a specification.

This invention relates to rail joints.

The object of the invention is to provide a rail joint of novel construction, which is very strong and durable and which will effectively prevent springing of the connected rail ends relatively to each other. To this end a rail joint of my invention comprises the various features and details of construction hereinafter described and claimed.

In the accompanying drawings, in which my invention is fully illustrated,

Figure 1 is a side view, partly in section on the line 1—1 of Fig. 3, of a rail joint of my invention, shown as applied in use for connecting two rails.

Fig. 2 is a top plan view thereof, partly in section on the line 2—2 of Fig. 3.

Fig. 3 is an end view of my improved rail joint, showing the rail in section.

Fig. 4 is a view substantially similar to Fig. 3, illustrating the manner of assembling the parts of my improved joint.

Figs. 5 and 6 are fragmentary top plan and end views, respectively, illustrating different means for preventing relative endwise movement of parts of my improved rail joint relatively to each other; and

Fig. 7 is a fragmentary view illustrating a contemplated modification.

Referring now to the drawings, A, A' designate rails joined end to end by means of my improved rail joint, a the bases of said rails, a', a² the webs and balls thereof, and a³ the ties which support said rails.

My improved rail joint comprises a base plate 1, the upper surface 2 of which forms the seat on which the bases a of the ends of the joined rails rest. Said base plate 1 also preferably acts as a tie plate, being of such length that it will extend over and rest upon at least two ties, and is preferably secured thereto by means of usual spikes, inserted through spike holes a⁴ in lugs formed on the base plate 1 and driven into the ties a³ in the usual manner.

Formed at the lateral edges of the base plate 1 are upwardly extending flanges 3

and 4, formed in the adjacent faces of which are grooves 5 and 6, which together form a channel adapted to receive the bases a of the joined rails and both the transverse and vertical dimensions of which are materially larger than the corresponding dimensions of said rail bases. Also, the width of the space between the adjacent or inner sides of the flanges 3 and 4 above the grooves 5 and 6 is less than the width of the rail bases, so that, in use, the upper sides 5', 6' of said grooves 5 and 6 will overlap both outer edges of the rail bases.

The upper sides 5' and 6' of the grooves 5 and 6 are inclined to the horizontal in substantially the same manner as the upper sides of the rail bases a, but at a greater angle. With the described construction, the channel between the flanges 3 and 4 will form in effect a dovetail.

To provide for conveniently engaging the bases of the rails and the channels in the base plates 1 formed by the grooved flanges 3 and 4 with each other, the distance from the bottom of either groove, as the groove 6, to the corner on the opposite flange, as the flange 3, formed at the intersection of the inner side of said flange and the upper side 5' of the groove 5 is greater than the width of the bases a of the rails. With the construction and relation described the rail bases may be inserted into or engaged with the channels in said base plates 1 by canting said rails and inserting an edge thereof into one of the grooves 5 or 6 in contact with the bottom of said groove, in which position the opposite edge of said rail base will clear the flange on said base plate other than that in which the groove is formed into which the first edge of the rail base was inserted, thus permitting the base of said rail to enter said channel with the bottom of the rail base resting on the seat 2 on said base plate.

Obviously, the base plates and rail bases may be engaged by manipulation of said base plates instead of the rails. This manner of engaging said base plates and rails may be employed in laying new track, but is of particular advantage in replacing a worn or broken rail or rails. Where conditions will permit, however, my invention contemplates equally engaging said base plates and rails by inserting said rails endwise into the channels formed in the base plates by the

grooved flanges 3 and 4, or what is the same thing, by passing said base plates endwise over the ends of the rails.

My improved rail joint also preferably 5 comprises usual fish plates 7 and 8, formed on the lower edges of which are wedges 9 and 10, said wedges being provided, respectively, with wedging surfaces 11 and 11' which co-act with corresponding wedging 10 surfaces 12 and 12' formed by the upper sides 5' and 6' of the grooves 5 and 6, to clamp the rail bases *a* firmly to their seats on the base plate 1.

As shown, the wedging surfaces 11 and 15 12 are inclined transversely only, while the wedging surfaces 11' and 12' are inclined both transversely and longitudinally, and the edge of the wedge 10 on the fish plate 8 20 and the bottom of the groove 6 in the flange 4 are inclined longitudinally to correspond with the inclination of the wedging surfaces 11' and 12', forming lateral wedging surfaces 13 and 14, whereby driving said wedge 10 endwise into the groove 6 will exert wedging 25 actions on the rail bases *a* both vertically toward the rail seat 2 and laterally into the groove 5, which will operate to clamp said rail bases firmly to their seats 2 on the base plate 1 and also to force said rail bases and 30 the outer edge of the wedge 9 into the groove 5, whereby the wedging surfaces 11 and 12 on said wedge 9 and on the upper side 5' of said groove 5 will coöperate with the wedging surfaces 11' and 12' to clamp 35 the rail bases rigidly to their seats 2 on the base plates 1.

The fish plates 7 and 8 and the wedges 9 and 10 having been adjusted into position, and the wedge 10 having been driven home 40 to lock the base plate 1 and the rail bases *a* together, which will also force the upper edges of the fish plates 7 and 8 into engagement with the bearing surfaces or shoulders formed on the under sides of the balls 45 *a*² of the rails, said fish plates are secured to the rails by usual bolts 15 inserted through said fish plates 7 and 8 and the webs *a*' of the joined rails in the usual manner, thus further locking the structure together, the 50 spring of the fish plates under the tension of said bolts 15 further strengthening the clamping action of the wedges 9 and 10 and of the base plate 1 with the rail bases *a*.

In order to insure that the base plate 1 55 shall not work loose, due to the pounding of trains passing over the tracks or from other causes, means are preferably provided for locking the base plate 1 and the wedge 9 against relative endwise movement, simple 60 means for this purpose consisting of interlocking parts on said base plate and wedge. As shown in Figs. 1-5, said interlocking parts consist of stop lugs 16 on the ends of the wedge 9 which embrace opposite ends of 65 the base plate 1, said lugs preferably form-

ing extensions of said wedge and being of such length that said wedge may be inserted into position by first moving the base plate 1 laterally to the limit of its movement represented by contact of the edge of said rail bases with the bottom of the groove 6 and sliding said wedge 9 endwise into the space between the sides of the groove 5 and the upper side of the rail base *a* which engages with said groove 5, as shown in Fig. 4. 75

If desired, however, the lugs for locking said base plate 1 and wedge 9 against relative endwise movement may be formed on the ends of the base plate in such position that they will closely embrace the ends of the wedge 9 when said wedge is inserted into position. This construction is shown in Fig. 6, in which said locking lug is designated by the reference numeral 16'. With the construction shown in Fig. 6, the wedge 9 is 80 designed to be inserted in position by first moving the base plate 1 laterally to bring the opposite edge of the rail base in contact with the bottom of the groove 6, as shown in Fig. 4, and inserting the wedge 9 by what 85 may be described as a rocking movement, the lateral edge of said wedge being inserted into the groove 5 above the rail base *a* and said wedge and the fish plate 7 on which it is formed, being seated by turning the same 90 about the outer edge of said wedge 9 which is confined at the bottom of the groove 5. If desired, this manner of inserting said wedge 9 and fish plate 7 may also be employed where locking lugs 16 are used, as 95 shown in Figs. 1-5, the described manner of seating said wedge and fish plate being illustrated in Fig. 4 of the drawings in connection with said lugs 16.

As shown in the drawings and as is standard construction on many railroads, the distance *x* from the outer edges of the rail base to the inner edges of the shoulders or surfaces 17 at the under side of the ball *a*² of the rail against which the upper edges of 105 the fish plates bear, is longer than the distance *y* from the outer edges of said rail bases to the outer edges of said shoulders or surfaces 17. 110

With this construction, it is obvious that 115 the wedging action of the wedges 9 and 10 will thrust the upper edges of the fish plates 7 and 8 into strong contact with said shoulders or surfaces 17, which will operate both to lock said fish plates in position and to 120 crowd their upper edges inwardly toward the web of the rail. Thus, while bolts 15 will still be necessary to secure the rails *A*, *A'* against relative endwise movement, they will be relieved almost altogether from tension incident to securing the fish plates 7 and 8 in place. In most cases also, it is probable that only two bolts will be used in connection with my rail joint instead of four or more now commonly used. 125

To reduce the cost of manufacture, I contemplate dispensing with the top wedging surfaces 11' and 12' formed, respectively, on the top side of the wedge member 10 and the upper side 6' of the groove 6. With this construction, in order to secure a sufficiently close fit between said wedge member 10 and the rail base a^5 in the groove 6, it will also be necessary to dispense with the transverse wedging surfaces between said wedging member 10 and the upper side 6' of the groove 6, as, otherwise, the action of the lateral longitudinal wedging surfaces 13 and 14 would force the transverse wedging surfaces 11' and 12' out of engagement, thus producing a loose fit of said wedging member 10 and the rail base a^5 in the groove 6, and would destroy the rigidity of the joint. In this modification, therefore, I form the upper side of the groove 6 parallel with the rail seat 2 on the base plate, with which a rigid position of the wedge member 10 contacts. Thus, while the action of the lateral, longitudinal wedging surfaces 13 and 14 will force the wedge member 10 and the rail bases a^5 laterally within the groove 6, such lateral movement will not affect the fit of said wedge member 10 and rail bases a^5 in said groove 6 or impair the rigidity of the rail joint.

This modification is shown in Fig. 7 of the drawings, in which a^5 designates the rail base, 1' the base plate, 4' a lateral flange thereon, 6² the groove formed therein, 8' the fish plate and 10' the wedge member formed at the lower edge of said fish plate 8'. Formed on the lateral edge of the wedge member 10' and at the bottom of the groove 6² are lateral, longitudinal wedging surfaces 13' and 14' adapted to crowd the opposite edge of the rail bases of the joined rails and the opposite wedge member into the groove formed in the flange at the opposite margin of the base plate, said wedge member and groove being provided with transverse wedging surfaces, all as in the preferred form of my improved rail joint shown in Figs. 1 to 6.

The upper side 6³ of the groove 6² is parallel with the rail seat on the base plate 1' and formed on the wedge member 10' is a rib 18, the upper edge of which rests in contact with the upper side 6³ of said groove 6² when the rail joint is assembled for use, thus at all times maintaining the fit of the rail base a^5 and the wedge member 10' in the groove 6² and the rigidity of the joint.

I claim:

1. A rail joint comprising a base plate provided on its upper surface with a rail seat, marginal flanges thereon provided with grooves in their adjacent sides, wedge members adapted to be inserted between the upper side of said grooves and the upper sides of the rail bases, said wedge members

comprising a first wedge member having transverse wedging surfaces and which terminates short of the bottom of the groove which it engages, and a second wedge member comprising a longitudinal wedging surface on its lateral edge, and said base plate being provided at the bottom of the groove which receives said second wedge member with a corresponding longitudinal wedging surface adapted to contact and co-act with the longitudinal wedging surface on said second wedge member and to force the opposite edge of the rail base and the first wedge member laterally into the groove engaged thereby, substantially as described. 70

2. A rail joint comprising a base plate provided on its upper surface with a rail seat, marginal flanges thereon provided with grooves in their adjacent sides, fish plates adapted to be secured to opposite sides of the joined rails, wedge members on the lower edges of said fish plates adapted to be inserted between the upper sides of said grooves and the upper sides of the rail bases, said wedge members comprising a first wedge member having transverse wedging surfaces and which terminates short of the bottom of the groove which it engages, and a second wedge member having a longitudinal wedging surface on its lateral edge, 80

and said base plate being provided at the bottom of the groove which receives said second wedge member with a corresponding longitudinal wedging surface adapted to contact and co-act with the longitudinal 90

wedging surface on said second wedge member and to force the opposite edge of the rail base and the first wedge member laterally into the groove engaged thereby, substantially as described. 100

105

3. A rail joint comprising a base plate provided on its upper surface with a rail seat, marginal flanges thereon provided with grooves in their adjacent sides, wedge members adapted to be inserted between the 110

upper sides of said grooves and the upper sides of the rail bases, said wedge members comprising a first wedge member having transverse wedging surfaces and which terminates short of the bottom of the groove 115

which it engages and a second wedge member comprising longitudinal wedging surfaces on its upper side and lateral edge, and said base plate being provided at the bottom and upper side of the groove which receives 120

said second wedge member with corresponding longitudinal wedging surfaces adapted to contact and co-act with the longitudinal 125

wedging surfaces on said second wedge member to clamp the rail base to its seat on the base plate and to force the opposite edge of the rail base and the first wedge member laterally into the groove engaged thereby, substantially as described. 130

4. A rail joint comprising a base plate 130

- provided on its upper surface with a rail seat, marginal flanges thereon provided with grooves in their adjacent sides, wedge members adapted to be inserted between the upper sides of said grooves and the upper sides of the rail bases, said wedge members having transverse wedging surfaces and comprising a first wedge member which terminates short of the bottom of the groove which it engages and a second wedge member having longitudinal wedging surfaces on its upper side and lateral edge, and said base plate being provided at the bottom and upper side of the groove which receives said second wedge member with wedging surfaces adapted to contact and co-act with the longitudinal wedging surfaces on said wedge member to clamp the rail base to its seat on the base plate and to force the opposite edge of the rail base and the first wedge member laterally into the groove engaged thereby, substantially as described.
5. A rail joint comprising a base plate provided on its upper surface with a rail seat, marginal flanges thereon provided with grooves in their adjacent sides, fish plates adapted to be secured to opposite sides of the joined rails, wedge members on the lower edges of said fish plates adapted to be inserted between the upper sides of said grooves and the upper sides of the rail bases, said wedge members comprising a first wedge member having transverse wedging surfaces and which terminates short of the bottom of the groove which it engages, and a second wedge member having a longitudinal wedging surface on its lateral edge, and said base plate being provided at the bottom of the groove which receives said second wedge member with a corresponding longitudinal wedging surface adapted to contact and co-act with the longitudinal wedging surface on said second wedge member to clamp the rail base to its seat on the base plate and to force the opposite edge of the rail base and the first wedge member laterally into the groove engaged thereby, substantially as described.
6. A rail joint comprising a base plate provided on its upper surface with a rail seat, marginal flanges thereon provided with grooves in their adjacent sides, fish plates adapted to be secured to opposite sides of the joined rails, wedge members on the lower edges of said fish plates adapted to be inserted between the upper sides of said grooves and the upper sides of the rail bases, said wedge members having transverse wedging surfaces and comprising a first wedge member which terminates short of the bottom of the groove which it engages, and a second wedge member having longitudinal wedging surfaces on its upper side and lateral edge, and said base plate being provided at the bottom and upper side of the groove

which receives said second wedge member with corresponding longitudinal wedging surfaces adapted to contact and co-act with the longitudinal wedging surfaces on said second wedge member to clamp the rail base to its seat on the base plate and to force the opposite edge of the rail base and the first wedge member laterally into the groove engaged thereby, substantially as described.

7. A rail joint comprising a base plate provided on its upper surface with a rail seat, marginal flanges thereon provided with grooves in their adjacent sides, wedge members adapted to be inserted between the upper sides of said grooves and the upper sides of said rail bases, said wedge members comprising a first wedge member having transverse wedging surfaces and which terminates short of the bottom of the groove which it engages, means for engaging said first wedge member with said base plate to prevent relative endwise movement thereof, and a second wedge member having a longitudinal wedging surface on its lateral edge, and said base plate being provided at the bottom of the groove which receives said wedge member with a corresponding longitudinal wedging surface adapted to contact and co-act with the longitudinal wedging surface on said second wedge member to clamp the rail base to its seat on the base plate and to force the opposite edge of the rail base and the first wedge member laterally into the groove engaged thereby, substantially as described.
8. A rail joint comprising a base plate provided on its upper surface with a rail seat, marginal flanges thereon provided with grooves in their adjacent sides, wedge members adapted to be inserted between the upper sides of said grooves and the upper sides of the rail bases, means for securing said wedge members to the joined rails when in use, said wedge members comprising a first wedge member having transverse wedging surfaces and which terminates short of the bottom of the groove which it engages, means for interlocking said first wedge member with said base plate to prevent relative endwise movement thereof, said means comprising stops on one of said interlocking members which embrace opposite ends of the other, and a second wedge member having a longitudinal wedging surface on its lateral edge, and said base plate being provided at the bottom of the groove which receives said second wedge member with a corresponding wedging surface adapted to contact and co-act with the longitudinal wedging surface on said second wedge member to clamp the rail base to its seat on the base plate and to force the opposite edge of the rail base and the first wedge member laterally into the groove engaged thereby, substantially as described.

9. A rail joint comprising a base plate provided on its upper surface with a rail seat, marginal flanges thereon provided with grooves in their adjacent sides, wedge members adapted to be inserted between the upper sides of said grooves and the upper sides of the rail bases, said wedge members comprising a first wedge member having transverse wedging surfaces and which terminates short of the bottom of the groove which it engages and a second wedge member having a longitudinal wedging surface on its lateral edge, and said base plate being provided at the bottom of the groove which receives said second wedge member with a corresponding longitudinal wedging surface adapted to contact and co-act with the longitudinal wedging surface on said second wedge member to clamp the rail base to its seat on the base plate and to force the opposite edge of the rail base and the first wedge member laterally into the groove engaged thereby, the dimensions of said base plate from the bottoms of the grooves therein to the corners of the flanges on said base plate opposite to said grooves, respectively, formed at the intersections of the inner sides of said flanges and the upper sides of the grooves therein being greater than the width of the rail base, substantially as described.
10. A rail joint comprising a base plate provided on its upper surface with a rail seat, marginal flanges thereon provided with grooves in their adjacent sides, wedge members adapted to be inserted between the upper sides of said grooves and the upper sides of the rail bases, said wedge members comprising a first wedge member having transverse wedging surfaces and which terminates short of the bottom of the groove which it engages and a second wedge member having a longitudinal wedging surface on its lateral edge, and said base plate being provided at the bottom of the groove which receives said second wedge member with a corresponding longitudinal wedging surface adapted to contact and co-act with the longitudinal wedging surface on said second wedge member to clamp the rail base to its seat on the base plate and to force the opposite edge of the rail base and the first wedge member laterally into the groove engaged thereby, substantially as described.
11. Rails the balls of which are provided on their under sides with bearing surfaces the distances from the lateral edges of the rail bases to the outer edges of said bearing surfaces being less than the distances from the lateral edges of said rail bases to points inside of the outer edges of said bearing surfaces, and a rail joint for connecting said rails, said rail joint comprising a base plate provided on its upper surface with a rail seat, marginal flanges thereon provided with grooves in their adjacent sides, fish plates adapted to be secured to opposite sides of the joined rails and provided on their upper edges with bearing surfaces fitted to the bearing surfaces on the under sides of the balls of the joined rails, wedge members on the lower edges of said fish plates adapted to be inserted between the upper sides of said grooves and the upper sides of the rail bases, said wedge members comprising a first wedge member having transverse wedging surfaces and which terminates short of the bottom of the groove which it engages, and a second wedge member having a longitudinal wedging surface on its lateral edge, and said base plate being provided at the bottom of the groove which receives said second wedge member with a corresponding longitudinal wedging surface adapted to contact and co-act with the longitudinal wedging surface on said second wedge member to clamp the rail base to its seat on the base plate and to force the opposite edge of the rail base and the first wedge member laterally into the groove engaged thereby, substantially as described.
12. Rails the balls of which are provided on their under sides with bearing surfaces the distances from the lateral edges of the rail bases to the outer edges of said bearing surfaces being less than the distances from the lateral edges of said rail bases to points inside of the outer edges of said bearing surfaces, and a rail joint for connecting said rails, said rail joint comprising a base plate provided on its upper surface with a rail seat, marginal flanges thereon provided with grooves in their adjacent sides, fish plates adapted to be secured to opposite sides of the joined rails and provided on their upper edges with bearing surfaces fitted to the bearing surfaces on the under sides of the balls of the joined rails, wedge members on the lower edges of said fish plates adapted to be inserted between the upper sides of said grooves and the upper sides of the rail bases, said wedge members having transverse wedging surfaces and comprising a first wedge member which terminates short of the bottom of the groove which it engages and a second wedge member having longitudinal wedging surfaces on its upper side and lateral edge, and said base plate being provided at the bottom and upper side of the groove which receives said second wedge member with wedging surfaces adapted to contact and co-act with the longitudinal wedging surfaces on said wedge member to clamp the rail base to its seat on the base plate and to force the opposite edge of the rail base and the first wedge member laterally into the groove engaged thereby, substantially as described.

6
rail base to its seat on the base plate and to force the opposite edge of the rail base and the first wedge member laterally into the groove engaged thereby, substantially as described.

In testimony, that I claim the foregoing as my invention, I affix my signature in the

presence of two subscribing witnesses this 19th day of October, A. D. 1916.

EMIL A. RUTISHAUSER.
